(57) **CLAIM**

The ornamental design for a food preparation tool, as shown
and described.

DESCRIPTION

FIG. 1 is a front, right side perspective of the food preparation
tool showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIGS. 1-7 of the food preparation tool are
for the purpose of illustrating environment, and form no part
of the claimed design.
